UNITED STATES PATENT OFFICE.

JOHN S. SMITH, OF JACKSON, MICHIGAN.

FEEDER FOR TILE AND SEWER-PIPE MACHINES.

SPECIFICATION forming part of Letters Patent No. 296,236, dated April 1, 1884.

Application filed January 28, 1884. (No model.)

To all whom it may concern:

Be it known that I, JOHN S. SMITH, of Jackson, in the county of Jackson and State of Michigan, have invented a new and useful Improvement in Feeders for Tile and Sewer-Pipe Machines, of which the following is a specification.

In the annexed drawings, making part of this specification, Figure 1 is a side elevation 10 of the feeder of a steam-pressure tile-machine, and Fig. 2 is an end elevation of the same.

The same letters are employed in both figures in the indication of identical parts.

The feeder is illustrated as applied to the 15 supplying of the cylinder X of a steam-pressure sewer-pipe machine. Such machines have heretofore been fed by hand, two workmen being usually employed in feeding the clay to the pressure-cylinder of such machines.

20 The clay, in proper condition, is raised by the endless-belt elevator A and poured upon the inclined endless apron B, which travels slowly around drums at either end and carries the clay to the endless apron F, placed at a right 25 angle to it, which apron F carries it and delivers it into the cylinder of the steam-press. Power is applied to the pulley G on shaft G', which carries the pulley F' and gives a speed to the endless apron F (encircling the two 30 twin pulleys F') of about six hundred feet per minute. The apron B moves slowly—say with a speed of fifteen feet per minute—and is actuated by a belt, F², on pulleys on the shafts E and D, properly proportioned to give the 35 reduced speed desired. The shaft D communicates motion to the bevel-wheel C on the shaft of the lower drum of the conveyer B by means of a double clutch, D', engaging one or the other of the bevel-pinions as it is shifted 40 by its hand-lever, in the ordinary manner.

The operator, by shifting the lever, may cause the endless apron to carry its load up or down, and this is provided for in order to stop the feed of clay to the cylinder at the time when 45 the plunger is forcing the clay through the die on the cylinder to form a section of pipe. When this has been accomplished, the apron B is made to feed down the clay upon the apron F. When the cylinder is filled, the movement 50 of the apron may be stopped or reversed, and to this end the elevator A should be arranged to deliver the clay midway of the apron B, so

that the latter may ascend while the cylinder full of clay is being discharged.

The surface of the apron F is smooth, no 55 cleats being used, and therefore the tendency of the apron is to outrun the clay, which will therefore be gathered into balls on its surface, and moving rapidly toward the cylinder when the apron curves down around the drum, the 60 tendency of the balls of clay will be to fly off on the tangent of the curve, and so they will be hurled with considerable force into the cylinder, thus filling it not only rapidly but compactly, the 65 impetus causing the clay to pack in the cylinder. To prevent the clay from being thrown over the cylinder, a shield (indicated by dotted lines in Fig. 1) is placed over the cylinder, facing the apron.

The apron B should preferably be wider 70 than the apron F, as it moves much more slowly. A series of friction-rollers may be placed underneath the apron F, to support it when the clay falls onto it from the apron B.

It should be understood that the speeds 75 stated are given approximately, being such as I have found practically efficient. In practicing my invention I have been able to dispense with the two men formerly required for filling the cylinder, and substitute a boy to operate 80 the lever and control the feeding-apron B, and have also increased the amount of work done in a given time by one-third.

The essential part of my invention is the rapidly-rotating apron F, arranged to ball and 85 hurl the clay into the cylinder of the press. The other parts indicated for feeding the clay to this apron may be modified variously without affecting the principle of my invention. By a "rapidly-rotating apron" I mean one moving 90 with sufficient velocity to form the clay into balls and hurl them into the cylinder.

What I claim as my invention, and desire to secure by Letters Patent, is—

1. In combination with the pressure-cylinder of a tile or sewer-pipe machine, a rapidly-rotating endless belt arranged in such relation to the cylinder of the press that when the apron descends around its pulley the clay carried on the face of the apron shall be hurled 95 by its centrifugal force into the open mouth of the cylinder, substantially as set forth.

2. In combination with the cylinder of a tile-machine, the endless apron F, feeding-apron

B, and reversible drum carrying the upper section of the latter alternately toward and from the former apron, substantially as set forth.

3. In combination, the cylinder or chamber to be fed, the rapidly-rotating apron F, and the apron B, supplying clay to the apron F, and mechanism imparting an intermittent motion to the apron B, substantially as set forth.

4. The combination of the endless apron B, to the bevel-wheel C upon the shaft of its driv-

ing-drum, bevel-pinions C' C', and double clutch D', for reversing the movement of the apron or stopping the same, substantially as set forth.

Witness my hand in the presence of two 15
subscribing witnesses.

JOHN S. SMITH.
